UNITED STATES PATENT OFFICE.

AUSTIN E. SLATTERY, OF MINNEAPOLIS, MINNESOTA.

SAFETY ENGINE-CRANKING DEVICE.

1,226,395.

Specification of Letters Patent. Patented May 15, 1917.

Application filed February 8, 1916. Serial No. 77,085.

To all whom it may concern:

Be it known that I, AUSTIN E. SLATTERY, a citizen of the United States, residing at Minneapolis, in the county of Hennepin and State of Minnesota, have invented new and useful Improvements in Safety Engine-Cranking Devices, of which the following is a specification.

This invention relates to safety engine cranking devices; the object in view being to provide in connection with an internal combustion engine, a starting crank, and means associated with said starting crank whereby, in case the engine shaft starts to turn in the wrong direction, the starting crank will be automatically disconnected from the engine shaft and locked in a safe position until the engine has ceased to turn in the wrong direction. The construction is of a simple character and is absolutely reliable in operation and avoids any possibility of the arm of the operator being injured or broken in case of back fire which is usually caused by advancing the spark of the ignition apparatus too far.

With the above and other objects in view, the invention consists in the novel construction, combination and arrangement of parts, as herein described, illustrated and claimed.

In the accompanying drawings:

Figure 1 is a front elevation of the cranking device of this invention illustrating the relation thereof to the cranking shaft of an internal combustion engine.

Fig. 2 is a side elevation of the same.

Referring to the drawings, 1 designates the cranking or starting shaft of an internal combustion engine, 2 the starting crank and 3 the crank handle.

At its inner end the starting crank 2 is provided with a hub 4 which surrounds the shaft 1, the bore of the hub 4 being of sufficient size to receive a sleeve 5 which passes entirely through the hub 4 and is provided at one end thereof with a ratchet wheel 6 having a fixed relation to the sleeve 5, said sleeve being threaded at its opposite end as shown at 7 to receive a nut 8 and a lock nut 9. The shaft 1 is slideable in the direction of its length through the sleeve 5 but is keyed to said sleeve as shown at 10 whereby the ratchet wheel 6 and the shaft 1 rotate together while at the same time the shaft 1 may be shifted in the direction of its length without affecting the ratchet wheel 6. The shaft 1 is provided at its inner end with

a clutch member 11 adapted to engage a corresponding clutch member on the adjacent end of the engine crank shaft (not shown), while at its opposite end the shaft 1 is by preference provided with a head 12 for the convenience of the operator in pushing the shaft 1 toward the engine shaft in order to bring the clutch member 11 of said shaft into engagement with the corresponding clutch member on the engine shaft.

13 designates an annulus preferably formed with a V-shaped periphery or working face 14. The annulus 13 is carried by a supporting frame 15 adapted to be fixedly secured to the frame of the machine or to the body of the engine so that the frame 15 and the annulus 13 are held stationary or prevented from rotating. 16 designates a sliding latch member, the inner extremity of which is adapted to engage the teeth of the ratchet wheel 6 as best shown in Fig. 1. The latch member 16 is slideable longitudinally of the starting crank 2 in a guide way 17 formed therein, the latch 16 being yieldingly held inwardly so as to engage the ratchet wheel 6 by means of a latch thrust spring 18 which is shown as encircling the reduced end portion of the latch member 16 and contained within a recess in the starting crank 2.

Pivots connected at 19 to the latch 16 is a latch retracting dog 20 having a clutch face 21 which is eccentric to the shaft 1, the face 21 being formed with a V-shaped groove preferably roughened or serrated as shown at 22 to engage the V-shaped periphery 14 of the stationary annulus 13. Extending from the dog 20 is a headed stem 23 around which is disposed a coiled expansion spring 24 the latter exerting its tension to hold the dog 20 in engagement with the periphery of the annulus 13. 25 designates a catch or detent which is carried by the starting crank 2 and provided with a lip or projection 26 adapted to engage a keeper 27 on the dog 20 when the latter is moved toward the center of the starting crank 2, the detent 26 serving to lock the dog 20 in firm engagement with the annulus 13 to prevent any reengagement between the latch 16 and the ratchet wheel 6.

From the foregoing description, taken in connection with the accompanying drawings, the operation of the cranking device will now be understood. When the starting crank 2 is moved in a clockwise direction,

the latch 16 is forced by means of the spring 18 into engagement with the ratchet wheel 6. The shaft 1 having now been pushed inwardly by pressure against the head 12 so as to cause an engagement between the clutch member 11 and a corresponding clutch member on the engine shaft, when the starting crank is turned in the proper direction, rotary motion is imparted to the 10 cranking shaft 1 and to the engine shaft. Should the engine back fire or should the engine shaft start to turn in an anti-clockwise direction, the dog 20 being in frictional engagement with the periphery of the stationary annulus 13, will be moved toward the center of the starting crank and in such movement, by reason of the eccentric disposition of the clutch face 21 of the dog 20, the latch 16 will be thrust out of engagement with the ratchet wheel 6 and the latch will be held locked in such inoperative position by the lip 26 of the catch 25 engaging the keeper or pin 27. Before operating the starting crank again, the catch 25 is disengaged from the pin or keeper 27 thus permitting the latch 16 to assume its operative relation to the ratchet wheel 6.

The mechanism hereinabove described is extremely simple in character, positive and reliable in operation, and may be applied to machines now in use, and when so applied, and in actual use, it will prevent injury to the arm of the operator for the reason that the starting crank is automatically released 30 as soon as the engine shaft starts to turn in the wrong direction.

Having thus described my invention, I claim:—

1. The combination of an engine starting 40 shaft, a ratchet wheel connected to said shaft to rotate therewith, a starting crank jour-

naled around said shaft as a center, a sliding latch member movable in a rectilinear path and carried by said starting crank, guiding means on said crank for said latch, a thrust spring for holding said latch normally in engagement with said ratchet wheel, a stationary annulus, and a latch retracting dog pivotally attached at one end to the latch and having a clutch face at its other end eccentric to the starting shaft and held against said annulus, said dog coacting with said annulus in one direction of movement of the starting crank to shift the latch out of engagement with said ratchet wheel. 45

2. The combination of an engine starting shaft, a ratchet wheel connected to said shaft to rotate therewith, a starting crank journaled around said shaft as a center, a sliding latch member carried by said starting crank, a thrust spring for holding said latch normally in engagement with said ratchet wheel, a stationary annulus, a latch retracting dog pivotally attached at one end to the latch and having a clutch face at its other end eccentric to the starting shaft and held against said annulus, said dog coacting with said annulus in one direction of movement of the starting crank to shift the latch out of engagement with said ratchet wheel. 50

means for locking said dog in latch retracting position, said means embodying a catch 60

pivotally carried by the starting crank, and a projection carried by the dog and adapted 65

to be engaged by said catch. 70

In testimony whereof I affix my signature in presence of two witnesses.

AUSTIN E. SLATTERY.
